UNITED STATES PATENT OFFICE.

JAMES G. SCOTT, OF WASHINGTON, DISTRICT OF COLUMBIA, ASSIGNOR TO SCOTT GAS APPLIANCE COMPANY, OF WASHINGTON, DISTRICT OF COLUMBIA, A CORPORATION OF DELAWARE.

GAS STOVE.

Application filed October 1, 1923. Serial No. 665,913.

To all whom it may concern:

Be it known that I, JAMES G. SCOTT, a citizen of the United States, residing at Washington, in the District of Columbia, have invented certain new and useful Improvements in Gas Stoves, of which the following is a specification.

This invention relates to gas stoves, and more particularly to gas stoves of the closed top type.

An object of the invention is the provision of means for maximum heat transfer to foods and solids cooked thereon at the same time maintaining perfect combustion under variations of pressure, specific gravity and heating values ordinarily encountered throughout both natural and manufactured gas distributions.

A further object of the invention is the provision of an improved arrangement of burners and means whereby perfect carbureting of primary and secondary air supply to each burner used on said stove causes an ultimate delivery to the stack or flue of flue gases, the analysis of which shows less than a dangerous amount of carbon monoxide and more than a safe amount of oxygen.

A further object is the provision of means for utilizing the surplus heat generated by the cooking top burners for the purpose of cooking food in an oven without lighting the oven burner.

A further object is the provision of means whereby the products of combustion may be passed directly through the stack, or through the oven to the stack, without interfering with the proper combustion of the fuel.

A further object is to provide an improved arrangement to supply secondary air to the lower oven of the stove which will prevent chilling of the upper oven when the lower oven is not in use.

In the accompanying drawings, I have shown one embodiment of the invention. In this showing:

Figure 1 is a horizontal sectional view of a stove on a line beneath the top of the burner compartments,

Figure 2 is a vertical sectional view on line 2-2 of Figure 1,

Figure 3 is a vertical transverse sectional view on line 3-3 of Figure 2,

Figure 4 is a detail perspective view of the flue through which the gases pass from the burner compartments to the stack,

Figure 5 is a horizontal sectional view on line 5-5 of Figure 4,

Figure 6 is a vertical sectional view on line 6-6 of Figure 4,

Figure 7 is a detail perspective view of the bottom plate of the top oven, and,

Figure 8 is a detail sectional view of the door of the lower oven on line 8-8 of Figure 2.

Referring to the drawings, the reference numeral 1 designates generally the lower supporting structure of the stove which is of the usual type and will, therefore, not be described in detail. It is provided with the usual legs 2, adapted to rest upon the floor. The burner section of the stove is provided with a removable top plate 3 having openings therein adapted to be closed by stove lids 4. A partition 5 is arranged beneath the top plate forming an upper compartment 6 and a lower compartment 7. This partition is provided with openings 8 and burners 9 are arranged in the lower compartment with the tops of the burners immediately beneath the partition 4. As shown, the openings 8 are surrounded by vertical flanges 10, forming stacks surrounding the burners. The lower compartment is closed at the bottom by means of a removable plate 11 of the usual construction, supported in suitable guides 12. This compartment is open at the front for the purpose of supplying secondary air to the burners, which air passes through the stacks formed by the flanges 10. A manifold pipe 13 is supported in suitable brackets 14 on the front of the stove in the usual manner and the burners are connected to the main feed pipes by burner arms 15. A burner arm 16 is arranged adjacent the oven side of the stove and is connected to a burner 17 in the lower oven. The flow of gas through the burner arms is controlled by means of cocks 18.

As shown, the compartment 6 is substantially rectangular in shape and is provided with two burners arranged in alinement transversely of the stove adjacent the oven and one larger burner adjacent the other side of the stove. The space at this side of the stove may be separated from the rest

of the compartment by means of a damper 19. This damper is supported in the plate 5 and is provided with a handle 21, extending in front of the stove. The compartment 6 is likewise connected to the top oven 22 by means of passage 23. A damper 24 is arranged in this passage. The damper is oscillating and is adapted to be controlled from the front of the stove by means of a handle 26.

A bottom oven 27 is arranged beneath the top oven and separated therefrom by a removable plate 28. The detail construction of this plate is shown in Figure 7 of the drawings. As shown, it consists of a pair of plates 29 and 30, slightly spaced from each other and connected by means of front and rear walls 31, the plates being separated at the sides to permit passage of gas and heated air as shown in Figure 2 of the drawings. The upper plate 29 is provided with a plurality of openings 32 and permit the gases to pass upwardly into the central portion of the top oven. The side walls of the top oven are provided with passages 33 through which the heated gases are adapted to flow and these passages are provided with openings 34, communicating with the interior of the oven. The top of the oven is formed of a pair of spaced plates 35 and 36. The lower plate is provided with openings 37 through which the gases are adapted to pass into a space 38 between the plates. There is a tendency to reduce the temperature of the oven by scrubbing and radiation, and to combat this, I place a sheet 39 of asbestos or other insulating material over the lower plate 36. This sheet is provided with openings 40, registering with the openings 37 in the lower plate. As shown, the rear end of the space 38 communicates with a stack 41.

When the oven is not being used and the damper 24 is in closed position to prevent the passage of gases through the oven, the gases from the compartment 6 are conveyed directly to the stack. As shown in Figures 4 to 6 of the drawings, I provide a flue 42 at the back of the stove, which flue extends horizontally and is divided by means of a partition 43 into a pair of chambers 44 and 45. The rear chamber 45 is provided with an opening 46, communicating with the compartment 6 to one side of the damper 19, whereby this portion of the compartment may be connected directly to the stack with the damper closed when the burners in the other portions of the compartment 6 are not in use. The chamber 45 communicates with the other portion of the compartment 6 through an opening 47. These two chambers in turn communicate with a passage 48 arranged behind the ovens which in turn communicate with the stack 41.

Heretofore, it has been customary to sup-

ply secondary air to the oven burner directly from the atmosphere and the difference in temperature between the interior of the oven and the room in which the stove is located causes a reduction in the temperature of the upper oven when the burner 17 is not lighted. The lower oven is provided with a hinged door 49 of the usual construction, consisting of an inner wall 50 and an outer wall 51. The outer wall is provided with a plurality of openings 52 and in the usual construction, the inner wall is provided with a like number of openings to permit uninterrupted flow of secondary air to the burner 17. In the present construction, however, I provide an inner wall with a reduced number of openings 53 so that only a small amount of air is drawn from the room while providing means for inspecting the flame. To supply the additional secondary air necessary for the operation of the burner 17, I provide an opening 54 in the side wall of the oven, communicating with the compartment 7 beneath the partition 5 and thus supply preheated air to the oven. When the lower oven is not being used, the air passing through it to the upper oven, is then at a much higher temperature.

The operation of the device will be apparent from the foregoing description. With the dampers 19 and 24 in open position, shown in Figure 2 of the drawings, the products of combustion in a heated state pass through the compartment 6 into the oven. It will be noted that the openings 46 and 47 to the flue are arranged level with the lower surface of this compartment and when the damper 24 is open, the natural tendency of heated gases to pass upwardly will cause the gases to flow into the top oven 22. This eliminates the necessity of a mechanically operated damper to close the openings 46 and 47 when the oven is being used. In the oven, the gases flow as indicated by the arrows, a portion of them passing between the plates 29 and 30, forming the bottom of the oven, to the passage 33 on the far side of the oven. Some of the gases passing through this space flow through the openings 32 into the central portion of the oven. The gases in the two passages 33 flow into the oven through the openings 34 and thence to the top space 38 through the openings 37. It will be apparent that the provision of an insulated top formed by the sheet 39 will maintain a higher temperature in the oven, as loss of heat by scrubbing or radiation is reduced to a minimum. The flow of gases through the passage 38 when the insulation is not provided, constantly draws heat from the oven into the room through the top plate 35 which is formed of metal and is therefore a good conductor of heat. When the space 38 is separated from the oven by insulation, practically the only

heat lost is the heat of the gases in the passage 38 which have served their purpose and are on the way to the stack.

As stated, the openings 46 and 47 arranged beneath the compartment 6, tend to retard the flow of gases from the compartment to the stack and when the damper 24 is closed and these gases are being sent direct to the stack, they flow very slowly from the compartment 6, whereby maximum efficiency of heating is obtained. When the lower oven is being used, the burner 17 is lighted and the gases from the lower oven pass upwardly through the top oven to the stack. By providing the opening 54, air is delivered to the lower oven in sufficient quantities to insure perfect combustion and in a preheated condition. This is of material importance when the lower oven is not being used, as the flow of air from the lower oven to the upper oven caused by the flow of heated gases through the upper oven heretofore had a tendency to reduce the temperature of the upper oven 10 to 15 degrees. The construction of the cooking top of the stove has been designed to afford substantially complete combustion and not chill the burner flame. An analysis of the stack gases shows a practical elimination of carbon monoxide, with a maximum temperature. This result is obtained by providing means for furnishing a balanced, uninterrupted flow of secondary air to the burners. Air is fed to the lower compartment at the front, and when the stove is operating, the flow of gases causes a "stacking" effect, around each of the burners, causing the air to flow upwardly within the flanges 10, through the burners by induced draft. The movement of the products of combustion toward the flues 44 and 45, or toward the oven, draws additional air to each of the burners through the flanged openings, and this process is continuous as long as the stove is in use. By providing the two flues 44 and 45, the volumetric proportion of the compartment 6 and the flue may be better proportioned and when one half of the stove is in use, the damper 19 may be closed. The partition 7, as stated, feeds the secondary air to each of the burners upwardly through the flanges 10, and this permits two or more burners to be arranged one behind the other, which has heretofore been impossible in closed top gas stoves.

It is to be understood that the form of my invention herewith shown and described is to be taken as a preferred example of the same, and that various changes in the shape, size and arrangement of parts may be resorted to without departing from the spirit of the invention or the scope of the subjoined claims.

Having thus described my invention, I claim:

1. In a gas stove, a burner compartment, burners arranged beneath said compartment and adapted to deliver the products of combustion into said compartment, an oven arranged to one side of and above said burner compartment and connected thereto to permit the products of combustion to pass upwardly through said oven, said oven being provided with a top formed of a pair of spaced walls providing a passage through which the products of combustion are delivered to the stack, the lower wall being provided with openings, and heat insulating means arranged in said passage adjacent the bottom wall thereof. 75

2. In a gas stove, a burner compartment, burners arranged beneath said compartment and adapted to deliver the products of combustion into said compartment, an oven arranged to one side of and above said burner compartment and connected thereto to permit the products of combustion to pass upwardly through said oven, said oven being provided with a top formed of a pair of spaced walls providing a passage through which the products of combustion are delivered to the stack the lower wall being provided with openings, and a layer of asbestos arranged in said passage on top of the lower wall. 90

3. In a gas stove, a top plate, a partition arranged beneath said top plate forming a compartment, said partition being provided with openings, burners arranged beneath said openings, and a horizontally disposed conduit arranged adjacent the rear of said compartment, said conduit being provided with an opening communicating with said compartment, said opening being substantially level with said partition. 105

4. In a gas stove, a top, burners arranged beneath said top, an oven arranged adjacent said top, a burner arranged therein, means for delivering air beneath said top to preheat it, and means for delivering said preheated secondary air into said oven. 110

5. In a gas stove, a lower supporting structure comprising side walls and a rear wall, the front of said supporting structure being open, a smooth top plate supported thereon, a partition arranged beneath said top plate, forming a compartment, said partition being provided with openings, burners arranged beneath said openings, and a lower plate arranged beneath said burners whereby air will be delivered in the chamber formed between said lower plate and said partition from the open front of said chamber. 120

6. In a gas stove, a lower supporting structure comprising side walls and a rear wall, the front of said supporting structure being open, a smooth top plate being supported thereon, a partition arranged beneath said top plate, forming a compartment, said 125

partition being provided with openings, and being further provided with flanges surrounding said openings and forming stacks, burners arranged beneath said openings, and a lower plate arranged beneath said partition forming a burner chamber, the front of which is open.

7. In a gas stove, an upper oven, a lower

oven, a partition separating said ovens, said partition being formed of a pair of spaced plates with their edges turned into contact, the upper plate being provided with a plurality of openings.

In testimony whereof, I affix my signature.

JAMES G. SCOTT.
